UNITED STATES PATENT OFFICE.

HARRY BRIDGMAN SMITH, OF NEW YORK, N. Y., ASSIGNOR, BY MESNE ASSIGNMENTS, TO HOAGUE-SPRAGUE CORPORATION, OF LYNN, MASSACHUSETTS, A CORPORATION OF MASSACHUSETTS.

BOX.

Original application filed January 12, 1923, Serial No. 612,172. Divided and this application filed July 17, 1926. Serial No. 123,201.

This application is a division of my application, Ser. No. 612,172, filed January 12, 1923, for boxes and methods of producing them, and relates to the box structures dis-
5 closed in said application.

An important object of the invention is to provide a box of novel construction which may be economically produced and in which wall bulging or warping is avoided by the
10 structure of the box.

More particularly stated, the object is to provide a box or box blank in which certain parts are made of separate pieces of material in order to facilitate the formation of the
15 blank into a box and to avoid warping of the walls which frequently occurs in cardboard shell boxes when the side walls are integral with the bottom section (or top section) of the box part. In the present embodiment
20 of the invention, the central or body section of the shell blank is integral with the end wings, and each side wing with connected corner laps, is distinct and originally separate from the body and end wing section,
25 these side wing sections being connected to the body section by foldable material such as a reenforcing or hinge strip, or by a cover sheet, or by both a hinge strip and cover sheet. The connecting material is substan-
30 tially thinner than the shell material, and admits folding the side wings without any strain thereon, either in the act of folding or after the parts are secured in final form, and therefore there is no force exerted upon
35 the side wings causing them to warp or bulge, as frequently happens in boxes of ordinary structure or made by ordinary methods.

Another object is to provide a structure
40 which realizes some or all of the above stated objects or advantages, and is made in the form of a simple uncovered shell, or a covered shell with or without connecting strips additional to the cover material.

45 The characteristics and advantages of the invention are further sufficiently explained in connection with the following detail description of the accompanying drawing, which shows one representative embodiment
50 of the invention. After considering this example, skilled persons will understand that

many variations may be made, and I contemplate the employment of any structures that are properly within the scope of the appended claims.

55

In the drawings:
Fig. 1 is a perspective view of a box blank embodying the invention in one form.

Fig. 2 shows the blank partly folded.

Fig. 3 shows the complete box part made
60 from the blank of Fig. 1.

Fig. 4 is a section at 4—4, Fig. 2.

Fig. 5 is a fragmentary section of the blank at 5—5, Fig. 1, in inverted position.

Fig. 6 is a similar section showing a
65 slight modification.

Fig. 7 is a fragmentary section at 7—7,
Fig. 1.

The complete box part is usually made by first producing a blank in flat form, as
70 shown in Fig. 1. This blank includes a layer of shell material, usually cardboard, straw board, chip board, or the like, in several distinct parts, represented in the present specific example by the main, central or body section *a* with integral end wings *d* defined by score or crease lines which are in this example, bead creases *k*; and side portions *b* with integral end- or corner-laps *c* defined by bead creases *k'*. The end wings may have
75 extensions *e* defined by bead creases *l*, for purposes hereafter explained, or these may be omitted.

The shell material constituting the strips
80 *a—dd* and *b—cc* are of course, much narrower than is necessary for ordinary structures and methods, wherein the shell material must be full width of the flat blank, and a great economy is therefore effected in
85 many cases because, for boxes of many dimensions, all of the strips and for the larger boxes the narrower strips may often consist of material which would otherwise be waste, and may, in fact, be trimmings produced, for example, in the production of other boxes. But even if such material is not available, the structure involving the separate shell strips is desirable for various
90 reasons explained above and hereafter, and therefore in some cases the strip material is provided in rolls of the proper width, or a wide roll may be split to produce the sepa-
95

100

rate strips before or as an early part of the production of the blanks, either by what I call "continuous" methods of my invention, as sufficiently explained in the above identified prior application, or any other method suitable for the production of the present structures.

The separate strips are usually spaced substantially apart, as shown in Figs. 1, 5, 10 6 and 7, and are connected together by connecting or hinge strips H, or by cover material C, or by both of these materials. If it is not desired to provide a covered box, of course the cover material is omitted, or in 15 some cases when suitable cover material is used, having the requisite strength, folding qualities, etc., the distinct connecting or hinge strips H may be omitted. For the greatest strength and stability, as well as to 20 provide a highly finished covered box, both connecting materials are usually employed. When the blank is produced by continuous methods of my invention, the connecting or hinge strips H, usually extend to the ends 25 of the blank, because the blanks are severed from a continuous assembly in which the hinge strips, as well as the other materials, are longitudinally continuous; but when the blanks are produced by other methods it is 30 not necessary for the connecting or hinge strips to extend longitudinally beyond the fold lines or creases k, k'. The connecting strips are adhesively applied and consist of almost any suitable sheet material having 35 the desired strength, toughness and folding qualities, kraft paper being a good example of suitable material, although other paper or even woven fabric may be used in some cases.

40 When a covered box is desired, the cover sheet C is applied to one face of the complete shell layer, usually the side to which the connecting strips H are applied so that the latter will be concealed in the completed 45 box, and longitudinal margins m of the cover paper may be provided when desired, turned and secured to opposite margins of the shell strips b—cc to provide a covered edge; or the margins may be omitted if an 50 exposed or "raw" shell edge is not objectionable.

If the blanks are produced by the continuous method with hinge or cover material or both extending to the ends of the 55 wings c—d, these connecting materials are slit or cut away longitudinally, usually on lines parallel with the inner edges of wings c and the outer longitudinal edges of wings d to provide for proper end and corner wing 60 separation.

The blank is folded in the manner sufficiently explained in Figs. 2 and 3, the folding or erection of the side wings b being accompanied by the bending of the hinge 65 strips or cover paper, or both, producing the

corner formation h, Fig. 4, the previously spaced adjacent edges of the respective shell strips being brought nearly or actually in contact, with the connecting materials smoothly overlying the joint. Since the 70 connecting material is relatively flexible, the folding on longitudinal lines is easily accomplished without any strain upon the shell material and therefore there is no tendency to warp or otherwise impair the desired 75 straight, flat form of the material and especially the side wings b, which are often warped or otherwise distorted when the shell blanks are of a single piece of material. The corner laps c are turned inward 80 as shown, and usually their confronting edges fit quite close together but are shown somewhat separated in order to better explain the structure.

The end wings are now turned up and secured by adhesive, as sufficiently indicated by stippling. When end wing extensions e are provided, these are folded over and secured to inner margins of the corner laps, as in Fig. 3, and serve to conceal the joint (or abutting edges of the corner wings) at the upper or open side of the box part and provide at the end edges a smooth covered surface without any exposed shell edge and particularly these extensions provide a 95 strong reinforcement for the box ends. Boxes are often subjected to greater strains at the ends than at the sides, because when placed on shelves the ends are usually outward and the end edges are grasped in pulling the boxes from the shelves and are often broken if the end structure is not substantial. The reinforcement provided by the end wing extensions enables these boxes to stand unusually rough treatment without 100 failure.

The blank and box described do not include any provision for covering the shell edges of the end wings d along the lines w, Fig. 3, but this is unobjectionable in many 110 cases and if it is desired to cover or conceal these edges, projecting portions of the cover material may be provided for that purpose, as explained in other pending applications.

The bead creases such as k, k' are desirable 115 in many cases, because they initially break or set the shell material in creased form and then when the parts are bent to final position the material folds readily along the crease lines without cracking or breaking. 120 The folded crease formation usually includes internal beads or projections such as k', Figs. 2 and 4. Any other style of crease or fold formation may be employed.

In producing the blank the hinge strip or 125 cover material, or these two proposed materials, may lie straight and flat across the space between the strips of shell material, such as a, b, Fig. 5, or to aid in the proper spacing in the shell strips and for other rea- 130

sons, the connecting material or materials may be somewhat indented or depressed into the space between adjacent edges of the shell strips, as at h' , Fig. 6.

5 It will now be understood that the invention in one of its broader aspects consists in providing a box blank or shell consisting of several distinct or originally separate strips of shell material, secured together by suitable flexible sheet material, to facilitate the folding of the blank to box form, without warpage and for other reasons, as fully explained above, and this important feature of the invention is not limited to the particular type of blank or box shown, but may be incorporated in other blanks or boxes having various wing formations, either uncovered boxes or those covered by the tight or loose wrap method.

10 I claim:

1. A box comprising a plurality of strips of shell material connected by adhesively applied relatively narrow strips of hinge material, and a sheet of cover material adhesively secured to and entirely covering one face of the combined shell strips over the hinge strips.

2. A box blank comprising a plurality of strips of shell material foldably connected by adhesively applied strips of relatively narrow, thin, tough, sheet material, and a sheet of cover material adhesively secured to and entirely covering one face of the combined shell strips over the hinge strips; said blank including a central or body section with integral end wings, and side wings with integral corner laps.

3. A box blank comprising a plurality of parallel strips of shell material connected by adhesively applied strips of hinge material, and a sheet of cover material adhesively secured on one face of the combined shell strips over the hinge strips, the blank being provided with transverse fold lines defining end wings integral with one of said strips and corner laps integral with the other of said strips.

4. A box structure comprising a plurality of separate pieces of shell or body material connected together along certain corner lines of the box structure by angularly folded and adhesively secured strips of hinge material, the box shell structure being substantially covered by adhesively secured sheet cover material overlying the connecting strips.

5. A paper box comprising a strip of shell material including a central or box body portion and end wing portions, two separate side strips of shell material each including a side wing portion and corner lap portions, said shell strips being foldably secured together along the edges of the body and side wing portions by thinner applied material,

outward surfaces of the shell strips being covered by shell covering material, said side and end wings being turned up, the corner laps turned inward and the end wings turned up and secured to the corner laps.

6. A paper box comprising a strip of shell material including a central or body portion and integral end wing portions, two side strips of shell material each including a side wing portion and integral corner lap portions, said shell strips being secured together along the edges of the body and side wing portions by hinge strips of flexible sheet material adhesively secured to margins of the shell material, outward surfaces of the shell strips being covered by adhesively applied sheet covering material, said side and end wings being turned up, the corner laps turned inward, and the end wings turned up and secured to the corner laps.

7. A paper box formed of a covered blank comprising three substantially parallel strips of shell material, the central strip including a box body portion and integral end wing portions, and the outer strips including side wing portions and integral corner lap portions, the body and side wing portions of the shell strips being foldably secured together by strips of flexible sheet material, similar surfaces of all of said strips being covered by sheet cover material, the blank being folded and secured in box form with the side wings turned at right angles to the body, the corner laps turned in at right angles to the body and the side wings, and the end wings turned at right angles to the body and secured against outer faces of the corner laps.

8. A paper box formed of a covered blank comprising three substantially parallel strips of shell material, the central strip including a body portion and integral end wing portions, and the outer strips including side wing portions and integral corner lap portions, the body and side wing portions of the shell strips being bendably secured together by connecting strips of flexible sheet material adhesively secured to adjacent margins of said shell strips, similar surfaces of all of said strips being covered by sheet cover material adhesively secured, the blank being folded and secured in box form with the side wings turned at right angles to the body, the corner laps turned in at right angles to the body and the side wings, and the end wings turned at right angles to the body and secured against outer faces of the corner laps.

Signed at New York city, in the county of New York and State of New York this 14th day of July A. D. 1926.

HARRY BRIDGMAN SMITH.
